Inventor

By *Clarence A. L. Brown*
Attorney

UNITED STATES PATENT OFFICE.

ROBERT HARRY MCCOY, OF CONDA, IDAHO, ASSIGNOR OF ONE-THIRD TO JOSEPH B. BELL, OF EVANSTON, WYOMING.

OIL CUP.

Application filed April 4, 1923. Serial No. 629,771.

To all whom it may concern:

Be it known that I, ROBERT HARRY McCoy, a citizen of the United States, residing at Conda, in the county of Caribou and State of Idaho, have invented certain new and useful Improvements in Oil Cups, of which the following is a specification.

In carrying out the present invention, it is my purpose to provide an oil cup, that is specifically adapted for application to connecting or pitman rods of all types of machines, with which I am now familiar, it being of course understood that I do not limit myself to the application of my device to pitman or connecting rods, as in the future practice, the device will operate equally as well as in conjunction with the movable elements of all machinery, the nature of the same being such as to automatically feed the oil to the parts when the machines are operating, but which will absolutely cut off the flow of oil when the machines are stopped, thereby overcoming a great wastage of fuel.

25 A further purpose of the invention is the provision of such an oil cup, that is comparatively simple of construction, and that will operate efficiently and effectively under all conditions, which may be installed and maintained at a minimum expense, and wherein the component parts will be so arranged and correlated as to reduce the possibility of derangement to a minimum.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:

45 Figure 1—is a side elevation of my improved oil cup, a portion of the casing being broken away.

Figure 2—is a detail vertical cross section thereof.

50 Figure 3—is a view similar to Figure 2, certain of the parts shown in side elevation.

Referring to the drawings in detail, my

device embodies the provision of an open ended cylindrical casing 5, the lower end of which is positioned within the plate 6, formed upon the upper end of a well known type of fitting 7, it being understood that between the lower end of this casing, and the said plate 6, there is interposed a packing ring 8. Upon the top end of the casing 5 is a closure cap 9, the same being formed centrally with an opening, surrounding which is a sleeve or collar 10, the same being formed with internal screw threads for the reception of a screw threaded filler plug 11, whereby lubricant may be placed into the cup when the plug is removed. As a means for retaining this plug within the sleeve or collar 10, there is provided a set screw 12, that engages through an opening in the collar and binds against the said filler plug. The plate 6 upon the end of the said fitting 7 is centrally formed with an upwardly extending neck 13, the same being provided with a central opening coextensive with the length of the passage through the fitting 7. Communicating with the interior of the cup and the said passage through the fitting 7 are inwardly extending and downwardly inclined oil passages 14.

The said neck 13 is externally screw threaded, and has positioned thereon what may be termed a sleeve 15, the opposite sides of this sleeve being formed with relatively elongated vertically extending arms 16, it being noted that this element is maintained in adjusted positions upon the neck, through the medium of binding screws 17. The communicating ends of the said passages 14 provide a valve seat for the headed end of the valve rod 18, and is freely movable within the opening of a neck 13, the upper end of this rod being pivotally connected at 19 to an arm 20, and is pivoted at 21, between the said arms 16 of the arm 13. The front end 95 of this arm 20 is weighted at 22, and extending parallel with the said arm and a slight distance thereabove is an arm 23, formed integrally upon the said arms of the neck 13. The front end of the member 23 is 100 slotted at 24 for engaging over a relatively elongated set screw 25, that is carried by the weighted end of the arm 22, the head of the said screw adapted for contacting the arm

23, for limiting the downward swinging movement of the arm 20, upon its pivot 21.

As a means for raising the arm 20 upon its pivot for consequently forcing the valve rod 18 downwardly, for preventing the passage of the lubricant from the cup to the fitting 7, there is connected to this arm at a point forwardly of its pivot one end of a hair spring 26, this spring being coiled 10 around a cross shaft 27 between the upper ends of the arms 16 of the neck 13, and secured thereto. The opposite end of this shaft projects outwardly of the arms 16, and one end carries a finger piece 28, while 15 upon the opposite end thereof is a ratchet wheel 29. Pivoted upon the arm 16 adjacent said ratchet wheel 29 is a dog 30, normally forced into engagement with the teeth of the wheel, through the instrumentality of 20 a band spring, it being of course understood that the shaft 27 may be rotated for increasing or diminishing the tension of the spring.

The cylindrical casing 5 is formed upon one side with an annular projecting portion 25 32, the front end thereof being open for the reception of a sight glass 33. For maintaining certain elements of the cup in their assembled relation, there is positioned upon the plate 6 of the fitting 7, a relatively oval-shaped plate 34, the same being provided with a comparatively large central opening 35, for permitting of the engagement of the plate over the fitting 7. Adjacent the opposite ends of the member 34, are formed 30 vertically extending rods 37, the upper ends thereof being screw threaded and adapted for engagement through openings 38 formed within the opposite ends of a plate 40, and is somewhat similar to the plate 34, it being 35 of course noted that this plate is positioned upon the top cap 9.

For permitting of the engagement of this plate over the sleeve or collar 10, the same is formed with a central opening 41, and when 45 the two plates are assembled as shown more clearly in Figure 1, retaining nuts 42 are positioned upon the said screw threaded ends of the rods 37.

In view of the above description, it will 50 at once be apparent that when my improved oil cup is positioned upon a movable element of a machine, such as a pitman or connecting rod, the movement thereof will occasion a rocking movement of the arm 20, in view 55 of the weighted end 22. Upon a downward rocking movement of this arm, the valve rod 18 will be raised for consequently permitting the flow of the oil from the cup through the fitting to the part to be oiled. As soon 60 as the machine is stopped, the spring 26 will maintain the valve rod 18 in its downward position for effectively cutting off the flow of oil, for thereby overcoming any wastage of the lubricant.

65 Although I have herein shown and de-

scribed the preferred embodiment of the present invention, it is nevertheless to be understood that minor changes may be made therein, without departing from the spirit and scope of the invention as claimed.

Having thus described my invention, what I claim as new, and desire to secure by Letters-Patent is:

1. An oil cup for attachment to movable members, including an oil receiving casing having an oil outlet, and unit carrying means removably mounted in the casing for controlling the oil outlet, having a supporting member for the units adapted for removable connection inside the casing, a lever 75 pivotally mounted in the supporting member pivotally mounting a valve on one end for closing said oil outlet and weighted at the other end so that said lever will be moved on its pivot for opening the valve in 80 the operation of the movable member, means for normally operating the lever to close the valve mounted in the supporting member and connected with said lever, and cooperating means carried by the lever and the 85 supporting member adapted for adjustment to limit the opening movement of the valve in the operation of the movable member.

2. An oil cup for attachment to movable members, including an oil receiving casing 90 having an oil outlet, and unit carried means having a supporting member formed with a threaded sleeve for co-operation with a threaded projection in the casing, and a pair of arms extending from said sleeves in 95 spaced parallel relation, a lever pivotally mounted intermediate its ends in and between said arms, carrying a rod at one end thereof formed with a valve at the lower end for co-operation with the oil outlet to 100 close the same and weighted at the opposite end, a winding shaft rotatable transversely between the upper ends of said arms, a hair spring mounted on said shaft having the free end extending and connected to said lever for normally operating the same to close the valve and outlet opening, means for rotating the shaft for adjusting the tension of said hair spring, means for normally 105 holding said shaft in adjusted position, a bifurcated projection on said arm extending outwardly over the weighted end of the lever and an adjustable member mounted in the lever extending through the bifurcation of said projection and co-operating therewith for limiting the movement of the lever and thereby the opening of the valve, for governing the oil outlet of the casing.

3. An oil cup for attachment to movable members, including an oil receiving casing having an oil outlet, and a controlling unit removably mounted within the casing, for controlling the oil outlet, having a valve for closing the outlet, a supporting member for the unit adapted for connection with the 125 130

casing, means carried by the supporting member connected with and carrying the valve and adapted for opening the same in the operation of the movable member, means carried by the supporting member engaging the last mentioned means for operating the same to hold the valve normally closed, and means carried by the valve carrying means cooperating with the supporting member and adjustable for limiting the opening movement of the valve.

In testimony whereof I affix my signature.

ROBERT HARRY McCOY.
